(57) **CLAIM**

The ornamental design of a housing portion for air conditioning apparatus as shown and described.

DESCRIPTION

FIG. 1 is a first perspective view of a design of a housing portion for air conditioning apparatus;

FIG. 2 is a second perspective view of the housing portion for air conditioning apparatus of FIG. 1;

FIG. 3 is a first side view of the housing portion for air conditioning apparatus of FIG. 1;

FIG. 4 is a second side view of the housing portion for air conditioning apparatus of FIG. 1;

FIG. 5 is a front view of the housing portion for air conditioning apparatus of FIG. 1;

FIG. 6 is a rear view of the housing portion for air conditioning apparatus of FIG. 1; and,

FIG. 7 is a top view of the housing portion for air conditioning apparatus of FIG. 1.

The broken lines and the areas within them depict portions of the housing portion for air conditioning apparatus that form no part of the claimed design.
